UNITED STATES PATENT OFFICE.

WALTER MYERS, OF BRIDGEPORT, CONNECTICUT, ASSIGNOR TO THE SINGER MANUFACTURING COMPANY, A CORPORATION OF NEW JERSEY.

SEWING-MACHINE.

1,137,654.

Specification of Letters Patent. Patented Apr. 27, 1915.

Application filed September 27, 1913. Serial No. 792,107.

To all whom it may concern:

Be it known that I, WALTER MYERS, a citizen of the United States, residing at Bridgeport, in the county of Fairfield and State of Connecticut, have invented certain new and useful Improvements in Sewing-Machines, of which the following is a specification, reference being had therein to the accompanying drawings.

10 This invention relates to improvements in sewing machines, and particularly that class commercially termed "Bonnaz" embroidery machines, substantially such as are represented by United States Patent No. 83,910, dated November 10, 1868, to A. Bonnaz.

20 Two forms of embroidery stitches are common to machines of this type, viz: the ordinary chain or crotchet stitch and the so-called drop or moss stitch; and the object of the present invention is to provide improved means for altering the character of the stitch without changing the operative relationship of the looper and its actuating 25 gear member.

30 In the earlier constructions, before changing the character of the stitch it is necessary to disconnect the looper from its driver and give to it a half turn and a like 35 adjustment to the needle, and in effecting these adjustments extreme care is essential to the proper retiming of the looper with respect to the line of needle actuation. In the present construction, when it is desired 40 to change the character of the stitch, instead of being obliged to change the relationship of the looper and its driver, it is merely necessary to give to the looper a half turn independently of the needle and feed-actuating mechanism and re-set the needle a half turn.

45 Reference being had to the accompanying drawings, Figure 1 is a view illustrating the present invention as applied to so much of a universal feed embroidery machine as is necessary to demonstrate its application; Fig. 2 an underside view of Fig. 1; Fig. 3 a view partially in full lines and partially in section of the elements comprising the 50 present invention, illustrating their application to the looper-actuating shaft; Fig. 4 details in perspective of the elements shown in Fig. 3 carried by the looper-actuating

shaft; Fig. 5 a perspective view of a portion of the looper and needle, illustrating their 55 relationship in the formation of a chain stitch seam; Fig. 6 a view similar to Fig. 5, illustrating the relationship of the loop-taker and needle in the formation of drop or moss stitches; Fig. 7 a plan view of the 60 needle-plate, it being broken out to show the upper end of the underlying thread-looper; Fig. 8 a view illustrating the formation of a succession of chain and drop 65 stitches; and Fig. 9 a view of one form of embroidery effected by the improved machine.

Referring to the figures, 1 represents the bed-plate, 2 the base of the arm standard, 3 the lower end of the head of the bracket 70 arm, 4 the tubular nipple, 5 the nipple-carrying tube, 6 the nipple-carrying tube bushing, 7 the feeding foot, 8 the needle, 9 the needle-plate, 10 the thread-looper, 11 the thread-looper-driving gear carried by 75 the thread-looper-actuating shaft 12, and 13 the gear-shaft provided with a gear 7' for operatively connecting, through the gear members 8', 9', 10', 11' and 13', the hand 80 crank 12' with the universal feed-directing and needle-turning mechanism of an embroidery machine of the variety represented by the patent previously referred to, the 85 only elements shown as located above the bed-plate of the sewing machine being 4, 5, 6 and 7.

14 represents a shaft bearing bracket suitably secured to the underside of the bed-plate and provided with bearing lugs 15 and 16 into which is journaled the tubular 90 bearing 17 carrying at one end the gear member 8' and at its opposite end the like gear member 9', the rear end portion 20 of said tubular bearing acting as a bearing 95 for the rear end of the shaft 12.

21 represents a guide collar adjustably secured by screw 22 on the shaft 12, said guide collar comprising the collar 23, arm 24, guide block 25 and detached shaft bearing 26, said two-part guide collar being a 100 preferred form of construction to meet the requirements of assembling, as shown in Fig. 3.

27 represents a shaft-adjusting cylinder having an extended portion 28 provided 105 with a forked end 29 and an enlarged

knurled extension 30, said cylinder being provided with a guide slot 31 into which tracks the guide block 25, and 32 is a spring for normally holding the forked end 29 in engagement with the forked end 33 of the shaft-adjusting cylinder stop 34, dogged with respect to the shaft 12 by the teat 35 of the screw 36 loosely entering the annular groove 37 (the latter and the teat 35 being shown in dotted lines only, Fig. 4) formed in the shaft 12, said stop tracking the guide slot 37' formed in the tubular bearing 17. The forked extension 28 and the forked stop element 34 comprise a clutch mechanism for maintaining given relative adjustments of the thread-looper and universal feed-directing mechanism and permitting of their relative adjustment to effect stitches of different character.

38 represents a rock-lever pivoted at 39 to a depending lug 40, the arm 42 of said lever being pivotally attached to the end of the shaft 12 to move said shaft in oppositely arranged longitudinal directions to cause the gear member 11 to transmit oscillatory stitch-forming movements to the thread-looper 10 and to permit its rotation independently of said pivotal connection, the arm 43 of said lever being connected by a universal joint 44 to the lower end of the shaft-oscillating rod 45, which latter is given oppositely arranged vertical movements from an eccentric (not shown) carried by an upper or main shaft (not shown) in a manner common to machines of the present type. The elements as 46 comprise parts of the stop-motion mechanism, but as the latter has no particular bearing on the present invention, further reference to such parts is deemed unnecessary.

Supposing the machine to be adjusted for effecting the chain stitch seam 47, as shown by Fig. 5, and it is desired to effect the drop or moss stitch 48, as shown by Fig. 6, the operator by moving the shaft-adjusting cylinder 27 in opposition to the resiliency of the spring 32 withdraws the forked end 29 from engagement with the forked end 33 of the shaft-adjusting cylinder stop 34, and when said ends are free and the crank handle is held against movement, the elements 10, 12, 21 and 27 are given a half turn, which positions the thread-looper as in Fig. 6, followed by permitting the forked end 29 to again engage the forked end 33, when the needle is adjusted from the position shown in Fig. 5 to that shown in Fig. 6, thus causing the thread-loop to be forced out of the open eye of the needle as the latter pierces the fabric, which effects the drop or moss stitch 48.

From the foregoing it is to be understood that the present invention is confined to the means employed for effecting relative adjustments of the thread-looper with respect

to the feed-directing mechanism without disengaging the thread-looper from its actuating shaft, and as the class of machines herein referred to is well understood by those skilled in the art, further description is deemed unnecessary.

What I claim is:—

1. In a sewing machine, the combination with a universal feed-directing mechanism, a stitch-forming mechanism including an open-eyed needle and thread-looper, and means for actuating said mechanisms including a thread-looper-actuating shaft, of a clutch mechanism comprising coacting forked members, one of which is adjustable axially and in the direction of its length for maintaining given relative adjustments of said thread-looper and clutch mechanism and permitting their relative adjustment for effecting stitches of different character. 85

2. In a sewing machine, the combination with a universal feed-directing mechanism, a stitch-forming mechanism including an open-eyed needle and thread-looper, and means for actuating said mechanisms including a thread-looper-actuating shaft, of a resiliently controlled clutch mechanism comprising coacting forked members, one of which is adjustable axially and in the direction of its length for maintaining given relative adjustments of said clutch mechanism and thread-looper and permitting their relative adjustment for effecting stitches of different character. 95

3. In a sewing machine, the combination with a universal feed-directing mechanism, a stitch-forming mechanism including an open-eyed needle and thread-looper, and means for actuating said mechanisms including a thread-looper-actuating shaft, of means including a spring-controlled clutch mechanism for maintaining given relative adjustments of said thread-looper and clutch mechanism and permitting their relative adjustment for effecting stitches of different character. 100

4. In a sewing machine, the combination with a universal feed-directing mechanism, a stitch-forming mechanism including an open-eyed needle and thread-looper, and means for actuating said mechanisms including a thread-looper-actuating shaft, of means including a spring-controlled clutch mechanism located between said shaft and feed-directing mechanism for maintaining given relative adjustments of said thread-looper and clutch mechanism and permitting their relative adjustment for stitches of different character. 110

5. In a sewing machine, the combination with a universal feed-directing mechanism, a stitch-forming mechanism including an open-eyed needle and thread-looper, and means for actuating said mechanisms including a thread-looper-actuating shaft, of 125

a clutch mechanism including coacting forked members carried by said shaft for maintaining given relative adjustments of the clutch mechanism and said feed-direct-
5 ing mechanism and permitting their relative adjustment for effecting stitches of different character.

In testimony whereof, I have signed my name to this specification, in the presence of two subscribing witnesses.

WALTER MYERS.
